DAMPENING MECHANISM FOR LITHOGRAPHIC OFFSET PRESSES AND THE LIKE

Joseph Schultz, Cleveland, Ohio

Application January 7, 1931, Serial No. 507,096

37 Claims. (Cl. 101—148)

My invention relates to dampening devices, and more particularly to mechanisms of this class suitable for supplying moisture to lithographic, printing and other reproducing and typographic apparatus. The particular embodiment of this invention disclosed in the present application illustrates this invention applied to a lithographic offset press.

This present invention is a continuation in part 10 of the application on which Patent No. 1,812,720, entitled Dampening device, was granted to me June 30, 1931. The present invention is, likewise, a further development of the subject matter disclosed in my pending application Serial No. 15 386,573, filed August 17, 1929 entitled Dampening device for lithographic offset presses or the like, and also a further development of the subject matter disclosed in my pending application Serial No. 504,786, filed December 26, 1930, entitled 20 Dampening device for lithographic offset presses and the like, and certain features disclosed but not claimed herein, are claimed in said application Serial No. 504,786.

Certain developments of the subject matter 25 disclosed in this application are shown in detail and are claimed in Patent No. 1,958,593, issued to me May 15, 1934.

As is well known, in the art of lithography, and especially in offset lithography, the printing 30 plate must be maintained adequately dampened. It is also well known that a certain minimum amount of moisture must be continuously supplied to the plate to prevent it from becoming coated with ink and irreparably damaged. It 35 is further a fact, that different portions or zones of the plate require different amounts of moisture, these different requirements arising from differences in the size and design of the printed areas.

40 The type of dampening apparatus which has been found satisfactory by long period of use and which has been approved and almost universally adopted for lithographic offset presses, comprises a reservoir of water or suitable liquid in which 45 a water roller is partially immersed. Adapted for intermittent contact with this water roller is a ductor roller which transfers the liquid from the water roller to an intermediate roller. This intermediate roller transfers the liquid to a plurality of dampening rollers which, in turn, distribute the liquid to the plate on the plate cylinder by rolling contact. This usual and well known distributing device is intended to supply a uniform amount of moisture over the entire 55 width of the plate cylinder.

It will be evident that such a uniform distribution is difficult to obtain because of unequal contacting pressure and consequent unequal moisture transfer at different points along the length of the rollers. This defect may occur 60 between the ductor roller and water roller or between any of the other rollers which perform the moisture transferring function. This unequal contacting pressure and consequent unequal liquid transfer may result from slight variations or irregularities in the diameter of any of the rollers, unequal adjustment of the two ends of adjacent rollers, spring or deflection of the center of any roller under pressure, variation in the water absorbing capacity of a roller covering, partial ink or grease coating on the covering of a roller, etc. It should be interpolated that with the above generally used apparatus, in some cases, when it is desired to reduce the amount of moisture transferred by the center of the rollers, it becomes necessary to press the ends of the rollers so tightly together that these ends become dry and collect ink from the plate, this being especially true in the case of long rollers.

It should be noted that even if the present 80 dampening apparatus did distribute the liquid uniformly, this would still not be the desired condition for most plates in modern high speed printing. It is well known that those portions of the plate which require the heaviest amount of ink will also need a heavier amount of dampening liquid than the portions requiring a relatively lighter amount of ink, or no ink at all. When the liquid is supplied in a uniformly distributed manner to such a plate, with the usual apparatus referred to above, the heavily inked portions will either not receive sufficient moisture, or the lightly inked portions will receive an over supply of moisture. The disadvantages resulting from the lack of the proper supply of moisture to every 85 portion of the plate in accordance with its requirements, are uneven color and lack of uniformity of color on the printed sheet. A deficient amount of moisture at any portion of the plate will cause what is known to the trade as "catching up" with ink. It is necessary, with the present apparatus, for the pressman to continuously 90 watch his plate. In order to correct the weak spots the pressman will supply more water to the entire width of the plate than is required and thus 95 overcharge certain portions. If he does not do this, it will be necessary for him to add water with a sponge to the dampening rollers at those places where more water is required. In an effort to 100 overcome these difficulties and in order to insure 105 110

the provision of sufficient liquid over the different areas of the plate without overcharging any portion of the plate, I have developed the apparatus to be hereinafter described.

5. The general object of my invention is to provide a device of novel design for supplying moisture to lithographic offset presses or similar printing apparatus, which will satisfactorily supply moisture to any portion of the plate where it is required, and which will supply this moisture in proportion to the requirements of such portion of the plate.

10. A further object of this invention is to produce a device which will correct the imperfections in moisture distribution caused by the defects in the construction or operation of the generally approved type of dampening mechanism.

15. A further object of this invention is to provide in this device means for varying the amount of water supplied, and to so construct this device that its water supplying function may be entirely interrupted.

20. A further object of this invention is to so mount this water supplying device that it may quickly be moved transversely of the direction of movement of the plate, thereby adapting this device to supply water to any point across the entire width of the plate.

25. A further object of this invention is to provide apparatus of this type which will function upon the novel principle, which consists in supplying a substantially uniformly distributed minimum amount of moisture to the dampening apparatus throughout its entire width, and adding controllable amounts of moisture to the dampening apparatus where the condition of the printing plate indicates that this moisture is required.

30. A further object of this invention is to provide apparatus of this type which can be depended upon to maintain the same rate of feed of liquid after having once been adjusted, to suit the requirements of the plate in the press, or of the dampening rollers, and which, accordingly, makes it unnecessary for the operator to continuously watch the moisture condition of the plate.

35. A further object of this invention is to so construct this device that it may be used with the generally approved and accepted type of dampening mechanism now in use on standard presses, and that it may quickly and easily be attached to such presses.

40. Another object of this invention, ancillary to the foregoing objects, is to insure longer life for the plate of the press due to the provision of the proper amount of moisture for every portion of the plate, thus eliminating the deleterious results from filling in with ink, due to an insufficiency of liquid on the one hand, and the defective printing resulting from an overcharging of liquid on the other hand.

45. A further ancillary object of this invention is to prevent the accumulation of excess acid water on the ends of the ink rollers and the consequent etching of these ink rollers so that they will not take ink, thus avoiding the necessity of counter-etching these rollers again so that they will take ink.

50. A further ancillary object of this invention is to provide means for keeping the dampening rollers and apparatus clean and free from ink, and to prevent the wear and tear on the dampening rollers due to the consequent brushing and scraping usually required to keep the rollers clean, thus reducing maintenance costs on these parts as well as eliminating the expense and de-

lay incidental to the repair, replacement and renewal of these dampening rollers and readjusting them to the plate.

55. Further objects and advantages of this invention will appear from the following description and from reference to the accompanying drawings. These annexed drawings and description set forth in detail certain means embodying this invention, such disclosed means constituting however, but one of a few of the forms in which the principle of this invention may be applied.

60. Referring to said annexed drawings:

65. Figure 1 is a fragmentary front elevational view of a portion of a standard lithographic offset press looking toward the plate cylinder and dampening device, certain parts of the press being omitted, this view being taken from the plane indicated by line 1, 1 in Figure 5.

70. Figure 2 is an enlarged fragmentary vertical section taken in the plane indicated in line 2, 2 Figure 1 and showing my improved dampening mechanism substantially in vertical cross section, certain parts being shown in an alternate position in broken lines.

75. Figure 3 is a plan view of the parts shown in full lines in Figure 2.

80. Figure 4 is a fragmentary cross sectional view through my improved water transferring belt, this view being taken in the plane indicated by line 4, 4 in Figure 2.

85. Figure 5 is a view partly in left side elevation and partly in cross section of a portion of a standard lithographic offset press equipped with my improved mechanism, the part of this view shown in section being taken in the plane indicated by line 5, 5 in Figure 1. This figure also shows a portion of my improved dampening mechanism in an alternate position in broken lines.

90. Figure 6 is a view similar to a fragmentary portion of Figure 2 showing certain parts adjusted to a different position.

95. Figure 7 is a cross-sectional view of a modified form of this invention embodying its broad features, this view being similar to Figure 10 in Patent No. 1,812,720 issued to me June 30, 1931.

100. Figure 8 is a perspective view of one of the elements shown in Figure 7 and corresponds with Figure 11 in said Patent No. 1,812,720.

105. The liquid used for dampening the plate of a lithographic offset press is usually either water or a relatively dilute solution of acid in water, or a dilute solution of gum arabic or other materials or combinations of materials in water, depending upon the requirements. In the following specifications and claims the terms water, moisture and liquid are used interchangeably, and it is understood that these terms are to include such liquids as are referred to above, or any liquids which may be used with this apparatus for the general purpose set forth.

110. In the drawings only so much of a lithographic offset printing press is illustrated as bears direct relation to this invention and to its location on the press and operation with the press.

115. In these drawings, with particular reference to Figures 1 and 5, 1 indicates the frame of the press, upon which are mounted in well known manner a paper or printing cylinder 2, a blanket cylinder 3, and a plate cylinder 4. These cylinders are rotated by suitable gears 5, 6 and 7 respectively, which are driven from a suitable source of power not shown.

120. The printing plate 8, is mounted on the plate carrying cylinder 4 in the usual manner. Ink rollers 9 are suitably mounted for peripheral con-

tact with the printing plate 8 as clearly shown. The balance of the inking mechanism including the ink fountain, ink distributing rollers and controlling mechanism is not shown, as these devices are well known to those skilled in the art and have no special bearing on this invention.

A usual type of dampening device, such as has generally been approved and adopted for lithographic offset presses and as shown in the drawings, will now be described. Two dampening rollers 10, 10 are mounted on the frame of the press for peripheral contact with the plate 8 on the plate cylinder 4. These dampening rollers 10 are usually covered with mohleton and are preferably so spaced that they contact one or more intermediate or distributing rollers 11, frequently mounted for axial reciprocation, one such roller 11 being shown in the drawings. Adjacent to this distributing roller or rollers 11 is mounted a ductor roller 12, preferably covered with mohleton, which is oscillatorily mounted to intermittently and alternately contact the distributing roller 11 and water roller 13. This water roller 13 is mounted on a shaft 14 located above the usual pan or reservoir 15 adapted to contain water or other suitable liquid. This pan is supported on the frame of the press in any desired manner. The roller 13 is preferably covered with suitable water absorbing material 16, in those presses in which this roller rotates at a relatively slow speed, and is frequently provided with a metallic surface in those presses in which this roller runs at a relatively higher rate of speed. The covering 16, when used, usually consists of a single layer of unbleached muslin, but any other suitable material or thickness of material may be used. The roller 13 may rotate either continuously or intermittently. When it rotates intermittently its rotation is usually simultaneous with its contact with the ductor roller 12 and mechanism is provided for varying the amount of its rotation.

The devices thus far described are quite well standardized on all lithographic offset presses, and their method of mounting and method of driving, while varying in some features on different presses, are well understood and need not be further described here in detail.

The dampening apparatus just described operates in the following manner: Water or other liquid is usually manually poured into the pan 15 and is maintained at the desired level by the operator. The periphery of the roller 13 being partially immersed in this bath of liquid, absorbs or conveys liquid by adhesion to its surface, which liquid is transferred to the ductor roller 12 at intervals. This ductor roller, in turn, transfers the liquid to the roller 11 which distributes the moisture to the dampening rollers 10, whence it is applied to the plate 8. It will be apparent that the intention of this device is to apply a uniformly distributed amount of moisture to the printing plate, across the entire face thereof.

Means are also provided in the standard type of apparatus, for regulating the intensity of pressure exerted by the ductor roller on its two adjacent rollers and for aligning this ductor roller therewith, and for aligning and regulating the pressure exerted by the other rollers upon each other. It will be evident that this method of liquid transfer is dependent upon the perfection of the several rollers and the accuracy of their alignment, and is affected by the lack of roundness, lack of uniform diameter, lack of uniform absorbing power of the covering and by any

spring or elasticity of the rollers between their supported ends. It will also be apparent that this system makes no provisions whatsoever for furnishing varying amounts of moisture simultaneously to different parts on the plate on the cylinder, nor does it provide means for supplying additional water where it may be employed.

My invention which is adapted to cooperate with and supplement the above apparatus, and to remedy its defects, and to augment its performance, will now be described. Referring particularly to Figures 1, 2, 3 and 5, a suitable pair of brackets 17 on the press, support a fixed shaft or rod 18. Adjustably mounted on this rod are a pair of arms 19 each provided with a cap 20 and screws 20^a, adapted for clamping the arms on the rod 18. One of these arms 19 is preferably mounted near each end of the shaft or rod 18 and each arm is provided at its lower end with a pin or bolt 21 upon which is mounted a second arm 22. Each of the arms 22 is formed with a bore, and a shaft or rod 23 is adapted to pass through the two aligned bores of these arms 22 as will be apparent from an inspection of Figures 1 and 3. Set screws 24 are provided to hold this rod 23 in position axially and rotatably.

The structure just described constitutes the support for one or more of my improved shiftable liquid feeding mechanisms. It will be apparent that the shaft 23 may be moved upwardly, downwardly, inwardly or outwardly with relation to the pan 15 and roller 13 by releasing the screws 20^a and/or bolts 21 and swinging the arms 19 and 22 to the desired position. It will also be apparent that the shaft 23 may be rotated in the aligned bores in the arms 22 upon the releasing of the set screws 24.

Mounted upon the shaft 23 are one or more of my improved liquid feeding mechanisms, which I indicate in their entirety by the numeral 25. 115 Two of these mechanisms are shown in full lines at 25 in Figure 1, and two additional mechanisms are suggested in broken lines at 25' in this figure. Inasmuch as all of these feeding mechanisms 25 are substantially identical in construction and 120 operation, it will only be necessary to describe one of these mechanisms.

The main housing or support for the operating parts of the dampening mechanism, is indicated at 26, this housing being formed at its lower end 125 with a bore 27^a in the hub 27. The diameter of the bore 27^a is slightly larger than the shaft 23 in order that the bracket 26 may have slidable engagement with the shaft or rod 23. This hub is provided with a thumb screw 28 which is adapted 130 to hold the bracket 26 in any desired position upon the shaft 23. Near its upper end, this housing is provided with a pin 29 upon which is mounted an intermediate pulley or roller 30. Likewise pivotally mounted upon this pin is a 135 regulator bracket 31. At its outer end this bracket is provided with a pin 32 upon which is mounted a head pulley or roller 33. Mounted in the bracket 26 at a point below the pin 29 and preferably in a direction toward the roller 13 is a pin 140 34 all as clearly shown in Figure 2. Loosely mounted on this pin is a small tail pulley or roller 35. Mounted in the bracket 26 is a thumb set screw 36 adapted to engage a segmental wall 37 of the regulator bracket 31, and hold it fixedly in 145 any desired angular position with relation to the bracket 26.

A novel form of water transferring belt is indicated at 38. This belt is preferably made of rubber or other suitable flexible material. This belt 150

is adapted to travel on the pulleys 30, 33 and 35 as shown in Figure 2, and for this purpose the inner surface 39 of this belt is relatively smooth. The outer surface of this belt is formed with a plurality of cups or pockets 40. These pockets are formed by a series of longitudinal partitions 41, five in number, as clearly shown in Figures 3 and 4, and by a series of cross partitions 42 as clearly shown in Figures 2 and 3. The longitudinal partitions 41 are formed substantially perpendicular to the outer surface 43 of the belt. The cross partitions 42 form an acute angle with the outer surface of the belt. The degree of hardness of the rubber or material of which this belt is made and the thickness of the walls must be so selected that the belt will readily pass around the small diameter of the pulleys, and so that, at the same time, the pockets 40 will not collapse in passing around the pulley 35.

In placing this improved feeding mechanism into operative position with the water roller 13 in the pan 15 the foot 26^a of the bracket 26 is rested upon the bottom of the pan 15, and this foot is preferably forced toward the water roller 13 as far as possible without unduly distorting the belt 38. The shaft or rod 23 is then fixed by clamping the screws 20^a and 21, following which the bracket 26 is fixed on the shaft 23 by tightening the set screw 28—thus securing the brackets in the desired position with relation to the roller 13 and the pan 15. The water regulator bracket 31 is then swung on its pivot pin 29 until the upper end of the belt occupies the desired relation to the roller 13 determined by the results required, as will be explained under the heading of operation.

It will be apparent from Figures 2 and 6 that the position selected for the regulator bracket will affect the arc of contact between the belt and the roller and will accordingly affect the length and area of the engaging surface. The position shown in full lines in Figure 2 shows substantially the greatest arc of contact obtainable between belt and roller, and lesser degrees of engagement are shown in broken lines in Figure 2 and in full lines in Figure 6. It should be noted that the belt rollers 30, 33 and 35 are so located with relation to the water roller 13 that the belt will maintain substantially the same degree of tautness for all usual operative positions of the belt on the water roller.

The belt 38 is moulded in the form of an endless ring or cylinder with the pockets on the outer periphery and, except when forcibly distorted, always tends to resume its original position. When mounted on this feeding device the belt is not permitted to assume the circular form but, as will appear from the broken line position in Figure 5, the location of the rollers 30, 33 and 35 is such that the belt, when removed from contact with the roller 13, assumes a form as close to the circular as possible. When this belt is caused to engage the periphery of the roller 13 a reverse bend is imparted to the belt which results in a distortion resisting pressure between the belt and the periphery of the roller 13. This pressure is, of course, greatest when the arc of contact is the greatest.

Operation

The operation of this improved dampening mechanism can best be understood by reference to Figures 2 and 6, and is as follows: As hereinbefore explained the roller 13 is rotated either intermittently or continuously by standard mech-

anism on the press. The contact of the outer surface of the belt 38 with the periphery of the roller 13 causes the belt 38 to travel by frictional actuation, in the same direction and at substantially the same speed as the periphery of the roller 13. As the belt becomes immersed in the bath of liquid and passes around the tail pulley 35 it collects water in the recesses or pockets 40. Aided by the forwardly and upwardly inclined cross partitions 42 this water remains in the pockets and is carried upwardly as the belt 38 moves upwardly. As soon as the outer surface 43 of the belt contacts the periphery of the roller 13, these recesses or pockets are closed and this water is entrapped in these pockets by the periphery of the roller 13. It will be understood that the extreme outer surface 43 of the belt, pressed tightly against the periphery of the roller 13 as previously explained, forms a sufficiently liquid tight seal to prevent the water from escaping from the pockets substantially until the belt 38, in passing to the pulley 33, leaves the periphery 16 of the roller 13. At this point the water is released and forms a coating of water on the surface of the roller 13 as is clearly shown, somewhat exaggerated, at 44 in Figure 2. It will be noted that the point of separation of the belt 38 from the roller 13, that is, the point of deposit of the water upon the roller 13, is located above the center of the roller and, in Figure 2, is located beyond the center, and that the water which is imprisoned in the pockets, will be distributed over the surface of the roller 13, for a width substantially equal to the width of the belt.

It is apparent that this amount of water will be more than is required for some places. When it is desired to supply a smaller amount of water to any part of the roller 13, the thumb set screw 36 is released and the water regulating casting 31 is rotated clockwise about the pin 29, as suggested in broken lines in Figure 2 and as shown in full lines in Figure 6. As will be apparent, when the arc of contact has been reduced as shown, some of the water released at the point of separation of the belt and the periphery of the roller, will run down the upwardly moving portion of the periphery of the roller 13 and therefore a smaller coating of water will be supplied to the downwardly rotating portion of the periphery of the roller 13 as shown at 45—Figure 6, thus making a thinner film of water available for the ductor roller under these conditions. The amount of supplemental water surcharged upon the water roller by the belt 38 may be varied from practically nothing to the maximum capacity of the mechanism, by adjusting the regulator casting 31.

The amount of water delivered to the roller by the belt can also be regulated by varying the position of the bottom of the belt with relation to the roller 13 and/or to relation to the level of the liquid in the reservoir 15. The bottom of the belt, which is mounted on the roller 13, may be moved away from the roller in a direction parallel with the level of the liquid by changing the angular position of the arms 19 and 22 one with relation to the other and swinging one or both, about the shafts 18 or 23. The bottom of the belt may be moved vertically with relation to the liquid by swinging the bracket 26 clockwise about the shaft 23, which results in a movement of the bottom of the belt in a direction substantially tangential to the periphery of the roller at the point of contact of the bottom of the belt with the water roller. Either one or both of the movements just described will result in a decrease in the amount

of water conveyed by the belt. It will be understood, of course, that a movement of the lower portion of the belt, necessitating a movement of the bracket 26, will require a movement of the adjusting arm 31 to properly locate the discharging point of the belt.

The water which is added to any zone of the water roller 13 is transferred, in turn, to the ductor roller 12, distributing roller 11, dampening rollers 10 and to the plate 8. I have found that this surcharged or supplementary water is transferred to the plate practically in line with its point of application to the water roller and without any substantial diffusion lengthwise of the rollers. In order to supply additional moisture to any portion of the printing plate, therefore, it is only necessary to determine the corresponding point on the water roller which delivers liquid to this portion of the plate, and locate this mechanism to feed the required additional water to this point on the water roller.

This water feeding mechanism above described, is accordingly mounted to permit its lateral movement so that it may be shifted to feed this supplemental liquid from the reservoir 15 to the water roller 13 at any point across the entire face of the roller, in order to satisfy the varied requirements of the printing plate. In order to shift this mechanism laterally it is only necessary to release the thumb screw 28, and the bracket 26 may be shifted laterally on the shaft 23 until it is opposite the desired place on the water roller 13, whereupon the bracket 26 may again be fixed by the tightening of the thumb screw 28. In order to permit the rapid movement of this mechanism laterally it may be desirable to swing the bracket outwardly away from the reservoir and roller 13, as shown in broken lines in Figure 5. The bracket 26 may be fixed in the position shown in broken lines in Figure 5 by clamping this bracket by means of the thumb screw 28, and this is the position occupied by this bracket when it is desired to entirely disengage the belt from the water roller.

Any number of these feeding mechanisms may be used with the water roller. Figure 1 shows two of these devices in full lines, and two devices in broken lines. The devices in full lines are placed opposite the two zones on the printing plate marked 8^a, 8^a, which are presupposed to call for a substantially solid inked portion and which will accordingly require a greater amount of water than other portions of the plate. The two dampening devices indicated at 25', at the respective ends of the roller 13, in broken lines, are shown at those places which usually require additional water because of the fact that the rollers are frequently so tightly pinched at the ends that they become relatively dry at these places and will collect ink from the printing plate unless water is surcharged at these places. This pinching of the rollers at the end is generally for the purpose of providing a sufficiently thin coating of moisture at the center of the rollers, and I have found that the use of one of these improved devices at each end of the water roller prevents any accumulation of ink at these points, thus eliminating the need for frequent cleaning of these rollers and thereby lengthening their life.

Alternative forms

Figures 7 and 8 illustrate a modified form of one of the important features of this invention, the form illustrated in these figures being an

earlier adaptation of this idea. In fact, these two figures are reproductions of Figures 10 and 11 of Patent No. 1,812,720 entitled Dampening device, with which the present application was co-pending in the United States Patent Office. Referring to these figures, 13' indicates a water roller covered with suitable absorbing material 16'. This water roller is mounted on a shaft 14' located above the usual pan or reservoir of water or other suitable liquid, which is not shown in this figure, but which is similar to the pan 21 as illustrated in Figure 8, for instance, in the said Patent No. 1,812,720, or to the pan 15 illustrated in this present application. This water roller 13' is assumed to be partially immersed in the bath of liquid contained in the reservoir or pan as will be understood.

An auxiliary trough independent of the pan or reservoir in which the water roller 13' is immersed, and preferably located above the same, is indicated at 46. This trough may be supplied with liquid in any desired manner, but preferably by means of a uniform feeding device such as the pumping system illustrated in Patent No. 1,812,720. This trough is provided with an overflow 47 which maintains the level of the liquid in the trough constant. Any liquid which passes over the overflow 47 is carried away by the drain pipe 48, and an additional drain pipe 48' is provided for emptying the trough. This trough 46 is provided with a metallic lining 49 which extends over one wall 46' of said trough, forming a curved lip 50 extending over said wall.

Guided upon this lip 50 and supported on the bottom wall of the trough 46 is a siphon capillary 110 wick element indicated in its entirety at 51. This element consists of a bifurcated spring finger 52 formed with a grip portion 53. A strip of molleton 54 is attached to the finger 52 preferably by stitching, substantially near the bottom of 115 the two legs 52 as shown at 55 and 56. The length of the molleton between the two stitched portions is such that the stitched portion 55 will rest on the bottom of the trough 46, when the upper portion 54' of the molleton loosely rests 120 on the curved lip 50. In this manner the element 51 is mounted in a stable yet loose manner on the curved lip 50 and bottom of the trough. An extension 57 of the molleton depends below 125 the stitched portion 56 and rests freely on the water roller 13'.

The element 51, by means of the molleton 54, will transfer liquid from the trough 46 directly to the water roller 13' by combined capillary and siphon action. It will be evident that the element 130 51 may be moved from one position on the wall 46' to any other desired position lengthwise of the trough, that is parallel with the axis of the roller 13'. In this manner additional liquid may be applied to any place on the water roller, as may be indicated by the requirements of the corresponding position of the printing plate. A plurality of these siphon capillary wick elements 51 is usually supplied for any one dampening device so that a sufficient number of these elements will be supplied to enable the operative to furnish supplementary liquid to all portions of the printing plate which may require additional moisture. It will be understood that the regulation of the amount of liquid supplied to any one 140 of these elements 51 may be obtained by lifting this element vertically on the wall, in which case the tension of the spring finger 52 will be sufficient to hold the element 51 in this adjusted position. It will also be understood that if any 145 750

one of the elements, or group of elements 51 is no longer required to supply water to the roller 13', these elements may be entirely removed from the trough 46.

6. The important features illustrated in Figures 7 and 8 which are similar to the features embodied in the preferred form of this invention are, (1) the provision of means for feeding liquid to a dampening member, and in turn to a printing plate, which is mounted so as to be shiftable transversely of the path of movement of the surface of the plate and/or of the dampening member and (2) the provision of means for adding liquid to a pre-coated dampening member, this means being movably mounted so as to be adapted to deposit this additional liquid upon any point across the face of the member. The device illustrated in Figures 7 and 8 differs from the preferred form of this invention in that the dampening member receives its uniform coating and its additional liquid from the same reservoir in the preferred form of the invention, while in the modified form of this invention the uniform coating of the dampening member is supplied by one reservoir and the additional liquid is supplied from another reservoir.

It will be evident that the invention above described may be embodied in many other forms without departing from the spirit and scope of this invention. It is apparent for instance, that the supplementary liquid need not necessarily be added to the water roller, but the liquid feeding mechanism may be mounted to feed the water to any one of the other rollers in the usual dampening apparatus. In fact, this laterally shiftable device may be mounted to feed the liquid to any other type of liquid distributing apparatus or member, such as a belt or apron for instance, or to any other mechanism adapted to transfer liquid to the printing plate. In its broader aspects this novel feeding device, manually shiftable to selected positions transversely of the path of movement of the plate, may be mounted to feed liquid directly upon the printing plate, which may, or may not, have been pre-moistened by any other means for supplying liquid. Many modifications may further be made in the details of construction of the apparatus shown. For instance, the water transferring belt 38 need not be provided with a plurality of regular individually distinct molded pockets. A sponge rubber comprising smaller pockets might be used to replace the molded pockets and, in fact, the material of which the belt is made need not be rubber, as any material which has the property of collecting water by adhesion or absorption and which is capable of transferring this water to another member, may be used, such for instance, as fabric material, felted molleton, etc. It will also be understood that these belts may be made of any desired width. It is also important to note that the belt element need not be loosely mounted and frictionally driven by a roller. My invention contemplates positive driving means for this belt element which may, or may not, be associated with the roller. This invention further may readily be altered to produce a device which will be portable so that it may be moved from one lithographic press to another, to perform the function described. This may be accomplished by substituting a slot, open at the bottom, for the bore 27' in the hub 27 of the bracket 26, which will permit the removal of this bracket and belt, by lifting, from the rod 23. It will be evident that each press with which such a portable device

is to be used, must be provided with a support corresponding with the rod 23.

Many other modifications of this invention and its application will naturally occur to those skilled in the art, and the present disclosures should therefore be considered as typical only, and I desire not to be limited to the exact construction shown and described.

What I claim is:

1. In a lithographic press, a printing plate movably mounted on said press, means adapted to feed a uniform coat of liquid to said plate, and an element adapted to feed additional liquid to a portion of said plate, said element comprising means for regulating the amount of additional liquid delivered and being shiftable in a direction transversely of the movement of said plate.
2. In a lithographic press, a printing plate, a distributing member, means for coating the distributing member substantially uniformly with liquid, an element adapted to feed additional liquid to said distributing member, said distributing member being adapted to transfer the liquid to said printing plate, and said element being movable transversely of said press.
3. In a lithographic press, a printing plate, a distributing member, means for coating the distributing member substantially uniformly with liquid, an element adapted to feed additional liquid to said distributing member, said distributing member being adapted to transfer the liquid to said printing plate, and said element comprising means for regulating the amount of additional liquid fed and being movable transversely of said press.
4. In a lithographic press, a printing plate movably mounted on said press, a source of liquid, a distributing member, means for uniformly coating said distributing member with liquid from said source, an element for superimposing additional liquid from said source upon said distributing member, said distributing member being adapted to transfer liquid to said printing plate, and said element being shiftable transversely of the direction of movement of said plate.
5. In a lithographic press, a printing plate movably mounted on said press, a reservoir of liquid, a moving distributing surface immersed in said liquid for a portion of its path of movement, and an element adapted to add liquid to said distributing surface after its immersion from said liquid, said element being shiftable in a direction transversely of the movement of said plate, and said surface being adapted to transfer liquid to said plate.
6. In a dampening device for a lithographic press, a bath of liquid, a travelling surface collecting a coating of liquid from said bath, and means adapted to superimpose a relatively narrow zone of liquid from said bath on said coated surface, said means being adjustable transversely of the direction of travel of said surface.
7. In a dampening device for a lithographic press, a bath of liquid, a roller having its lower periphery immersed in said bath, and mechanism adapted to deposit a relatively narrow coating of liquid from said bath upon the upper periphery of said roller, said mechanism being adapted to move parallel to the axis of said roller, whereby said relatively narrow coating may be deposited at any point along the length of said roller.
8. In a dampening device for a lithographic press or the like, a plurality of dampener rollers adapted to distribute water, a bath of water, and

- mechanism actuated by one of said rollers adapted to transfer water from said bath to one of said rollers, and means for regulating the amount of water transferred, said mechanism being mounted for adjustment in a direction parallel with the axis of said roller. 5
9. In a dampening device for a lithographic press or the like, a bath of water, a roller, and an endless flexible belt adapted to lift water from said bath, comprising a relatively smooth inner face and a plurality of recesses on its outer face, said outer face engaging a portion of the periphery of said roller. 10
10. In a dampening device for a lithographic press or the like, an endless rubber belt adapted to lift water, comprising a plurality of pockets longitudinally separated by partitions inclined with relation to the plane of the belt. 15
11. In a dampening device for a lithographic press or the like, a roller, a bath of liquid, and a relatively narrow travelling belt partially immersed in said liquid and adapted to transfer liquid to said roller, said belt being mounted in a mechanism adapted to shift said belt in a direction parallel with said roller and adapted to fix 20 said belt in said shifted position.
12. In a dampening device for a lithographic press or the like, a bath of liquid, a roller partially immersed in said bath, a movable belt, mounted on a plurality of pulleys adjacent said 25 roller, adapted to be actuated by said roller and adapted to transfer liquid from said bath to said roller.
13. In a dampening device for a lithographic press or the like, a bath of liquid, a roller partially immersed in said bath, a movable belt, mounted on a plurality of pulleys separate from 30 said roller, adapted to deposit water from said bath upon said roller, and means for regulating the amount of liquid deposited. 35
14. In a dampening device for a lithographic press or the like, a roller, a bath of liquid, and a travelling belt partially immersed in said liquid and adapted to transfer liquid to said roller, and means for regulating the depth of immersion of 40 the belt in the liquid.
15. In a dampening device for a lithographic press or the like, a roller, a bath of liquid, means, comprising a water transferring belt, adapted 45 to transfer water from said bath to said roller, said belt being adjustably mounted for movement toward and from the axis of said roller and in a direction parallel with said roller, and means for holding said belt in said adjusted position. 50
16. In a dampening device for a lithographic press or the like, a roller, a bath of liquid, a relatively narrow water transferring belt adapted to contact the periphery of said roller and means for varying the area of said contact, said belt being shiftable in a direction parallel with the 55 axis of said roller. 60
17. In a dampening device for a lithographic press or the like, a bath of liquid, a rotatable roller partially immersed in said bath, a movable water carrying belt adapted to contact a portion 65 of the periphery of said roller and means for varying the arc of contact between said belt and said roller. 70
18. In a dampening device for a lithographic press or the like, a bath of liquid, a roller having a portion of its periphery submerged in said bath, a movable liquid transferring belt contacting the periphery of said roller, and means for varying the point of separation of said belt and said 75 periphery. 80
19. In a dampening device for a lithographic press or the like, a rotatable roller, a bath of liquid, a movable belt partially immersed in said bath and contacting said roller and adapted to transfer liquid from said bath to said roller, and means adapted to regulate the depth of immersion of said belt in said bath, and means adapted to vary the point of deposit of the liquid by said belt upon said roller. 85
20. A device for lifting water comprising a rotating roller and a movable belt formed with a plurality of recesses on its outer surface, said outer surface contacting the periphery of said roller for a part of the path of movement of said belt and means adapted to partly fill said recesses with water prior to the contact of said surface with said belt. 90
21. In a dampening device for a lithographic press or the like, a bath of liquid, a roller partially immersed in said bath, and a device adapted to transfer liquid from said bath to said roller, comprising an endless belt running on a plurality of pulleys, at least one of said pulleys being mounted for movement toward and from the periphery of said roller. 95
22. In a dampening device for a lithographic press or the like, a roller, a bath of liquid and a movable belt adapted to transfer liquid from said bath to said roller, said belt being mounted in a pivotally supported bracket. 100
23. In a lithographic press, a movable plate, a liquid distributing device, a bath of liquid, a travelling surface collecting a coating of liquid from said bath, and means adapted to superimpose liquid from said bath upon said coated travelling surface, said travelling surface being adapted to transfer the coating of liquid to said distributing device and said distributing device being adapted to transfer said liquid to the plate. 110
24. In a dampening device for a lithographic press or the like, a roller, a bath of liquid, and means adapted to deposit liquid from said bath upon said roller in a relatively narrow zone, said means being axially movable substantially across the entire face of said roller, whereby said zone of liquid may be applied at any position upon said roller. 115
25. In a lithographic press, a movable plate, a water distributing device adapted by contact to transfer water to said plate, and an appliance for supplying water to said device, said appliance comprising a bath of water, a roller partially immersed in said bath, and means for delivering water from said bath to the upper half of said roller. 120
26. In a lithographic press, a printing plate mounted on a rotatable cylinder, a plurality of liquid feeding units each adapted to feed liquid to a portion of said plate, and said units each being individually adjustable in a direction parallel with the axis of said cylinder. 125
27. In a lithographic press, a printing plate mounted on a rotatable cylinder, liquid distributing means extending transversely of said press and adapted to apply liquid to the surface of said plate by contact therewith, and an element adapted to feed liquid to a relatively narrow portion of said distributing means, said element being mounted on a transverse member on the press and shiftable on said member transversely of the press substantially across the entire width of said plate. 130
28. In a lithographic press, a printing plate mounted on a rotatable cylinder, liquid distributing means extending transversely of said press and adapted to apply liquid to the surface of said plate by contact therewith, and an element adapted to feed liquid to a relatively narrow portion of said distributing means, said element being mounted on a transverse member on the press and shiftable on said member transversely of the press substantially across the entire width of said plate. 135
29. In a lithographic press, a printing plate mounted on a rotatable cylinder, liquid distributing means extending transversely of said press and adapted to apply liquid to the surface of said plate by contact therewith, and an element adapted to feed liquid to a relatively narrow portion of said distributing means, said element being mounted on a transverse member on the press and shiftable on said member transversely of the press substantially across the entire width of said plate. 140
30. In a lithographic press, a printing plate mounted on a rotatable cylinder, liquid distributing means extending transversely of said press and adapted to apply liquid to the surface of said plate by contact therewith, and an element adapted to feed liquid to a relatively narrow portion of said distributing means, said element being mounted on a transverse member on the press and shiftable on said member transversely of the press substantially across the entire width of said plate. 145
31. In a lithographic press, a printing plate mounted on a rotatable cylinder, liquid distributing means extending transversely of said press and adapted to apply liquid to the surface of said plate by contact therewith, and an element adapted to feed liquid to a relatively narrow portion of said distributing means, said element being mounted on a transverse member on the press and shiftable on said member transversely of the press substantially across the entire width of said plate. 150

- and contacting said plate, and a plurality of elements each adapted to feed liquid to a relatively narrow portion of said distributing means, said elements each being individually shiftable transversely of the press.
29. In a lithographic press, a printing plate mounted on a rotatable cylinder, a reservoir of liquid mounted on said press, a capillary device adapted to feed liquid from said reservoir to a relatively narrow portion of said plate, said device being mounted on said press and being shiftable relatively to said reservoir in a direction parallel with the axis of said plate, and adapted to vary the amount of liquid fed from said reservoir.
30. In a lithographic press, a printing plate mounted on a rotatable cylinder, and a relatively narrow capillary wick element adapted to feed liquid to a relatively narrow portion of said plate, said element being provided with a holder of substantially the same width as the element and supported on a member extending transversely of the press, said member being adapted to permit the shifting of the element in a direction parallel with the axis of the cylinder.
31. In a dampening device for lithographic presses or the like, a reservoir of liquid, a roller, and a portable element adapted to transfer liquid by capillarity and siphon action from said reservoir directly to said roller, said element adapted to be axially moved with relation to said roller, and portable means for holding said element in position.
32. In a dampening device for lithographic presses or the like, a reservoir of liquid, a roller and a liquid absorbent element, one portion of said element being immersed in said liquid and another portion being in contact with said roller, said element adapted to be axially moved with relation to said roller, and means movable with the element adapted to hold the element in operative position.
33. In a dampening device for a lithographic press, a reservoir of liquid, a roller partially immersed in said liquid, an auxiliary reservoir of liquid, and means adapted to transfer liquid from said auxiliary reservoir to said roller, said means being movable in a direction parallel with the axis of said roller.
34. In a dampening device for a lithographic press, a reservoir of liquid, a roller partially immersed in said liquid, an auxiliary reservoir of liquid and a wick element adapted to transfer liquid from said auxiliary reservoir to said roller, said element being mounted in a portable holder adapted to be adjusted axially along said roller.
35. A liquid feeding device adapted to supply liquid to a lithographic plate mounted on a plate cylinder, comprising a reservoir of liquid and a portable element adapted to feed liquid by capillarity and siphon action from said reservoir, means adapted to transfer said liquid to said plate, said element being adapted to be axially moved with relation to said plate cylinder, and being adapted for adjustment with relation to said reservoir for varying the amount of liquid fed by said element.
36. In a lithographic press, a printing plate mounted on a rotatable cylinder, means for coating the plate with moisture, and a device adapted to feed additional moisture to a relatively narrow portion of said plate, said device being shiftably mounted on a member extending transversely of the press.
37. In a lithographic press, a printing plate mounted on a rotatable cylinder, means adapted to coat said plate with liquid, a reservoir of liquid mounted on said press, a device adapted to feed additional liquid from said reservoir to a relatively narrow portion of said plate, said device being mounted on said press and being shiftable in a direction substantially parallel with the axis of said plate.
